Inventor
Clifford R Randall

UNITED STATES PATENT OFFICE.

CLIFFORD R. RANDALL, OF COUNCIL BLUFFS, IOWA.

AUTOMATIC CASH-DRAWER.

1,389,981.

Specification of Letters Patent. Patented Sept. 6, 1921.

Application filed June 25, 1920. Serial No. 391,771.

To all whom it may concern:

Be it known that I, CLIFFORD R. RANDALL, a citizen of the United States, residing in Council Bluffs, in the county of Pottawattamie and State of Iowa, have invented certain new and useful Improvements in Automatic Cash-Drawers, of which the following is a specification.

The purpose of this invention is primarily to provide a cash drawer operably engageable with a hand actuated visible adding machine, such for instance as the Burroughs, whereby upon operation of the machine the drawer is automatically opened.

Further objects are in the provision of means for maintaining the drawer in a locked condition, except upon full movement of the crank handle of the machine, and also for giving an audible signal when the drawer is opened.

These objects are attained by the novel construction, combination and arrangement of parts hereinafter described and shown in the accompanying drawings, forming a material part of this disclosure, and in which—

Figure 1 is a side view of drawer with the wall of the casing removed.

Fig. 2 is a broken plan view with cover removed.

Fig. 3 is a broken side view showing bell operating mechanism.

Referring to the drawings in detail, the numeral 10 designates a conventional type of adding machine or like mechanism operated by an extending handled crank 11 and provided with feet 12 adapted to enter the depressions 14 formed in the top or upper surface of a rectangular casing or box 15 tightly closed upon all sides except the front.

This casing may preferably be made of wood, highly polished and finished ornamenteally to agree with its surroundings, and adapted to rest upon a desk, table or like level surface.

The front 16, of the drawer 17, when closed covers the opening to the casing, preventing intrusion.

The interior of the drawer may be formed to receive bills of various denominations and contain tills for coins, the drawer being supported by angles resting on anti-friction rollers at its sides, the angles running in appropriate grooves, in the sides of the casings, as shown.

Attached to the inner surface of the rear

wall of the casing are brackets 20 in which is rotatably mounted a round bar 22 having rigidly secured to its end, adjacent the right hand side of the casing, a short arm 23, in 60 which is affixed a pin 24.

Also secured to the bar 22, at approximately the center of the casing, is a hook 25 having a beveled lower surface adapted to slide over a projection 26 formed with a detent 27, rigidly fixed in the rear wall of the drawer 17, so as to engage the same and hold the drawer tightly closed.

A lever 28 is pivoted at a point near its front end on a screw stud 29 set in the 70 inner side of the casing, the inner, longer extending end of the lever terminating in forks 30 between which is loosely engaged the pin 24, thus conveying motion to the bar 22.

At the front end of the lever 28 is pivotally attached a plunger rod 31, the same extending upward through an opening 32 in the casing cover and carrying at its extended end a roller 33, normally held in a 80 raised position due to the pull of a tension spring 34 attached at its ends respectively to the casing cover and lever.

Fixed to the handle crank 11 of the machine or to the shaft on which it is engaged, 85 is a cam 35 so positioned relative to the crank that as the same is turned in a forward direction horizontally downward, as in operating the machine, it makes contact with the roller, depressing the plunger, and by 90 the described intervening mechanism, raises the hook, thus releasing the drawer.

Disposed in the space between the inner end of the drawer and rear wall of the casing is one or more conically wound helical 95 push springs 36 secured at their larger ends to the casing wall and adapted to propel the drawer outward upon its release in a well understood manner.

Also in this space, at the side opposite the lever 28, a bell 37 is fixed to the casing and contactable with it is a hammer 38 pivoted to the side wall by the screw 39 and held in a normally vertical position by the tension spring 40 attached at one end to the hammer 100 stem hub and at the other to the casing.

A spring strip 41 extends rearwardly from the side of the drawer and is formed into a hook 42 engageable with the hammer stem so as to draw the same forward until released by the continued movement of the drawer, whereupon it rebounds and strikes 110

the bell, giving an audible signal that the drawer has been opened, the return of the drawer resetting the hook for further action.

From the foregoing it will be seen that a neat, comprehensive and practical money drawer has been disclosed capable of fulfilling the objects and purposes mentioned.

Having thus described my invention and set forth the manner of its construction, application and use, what I claim as new and desire to secure by Letters Patent, is:—

1. In a device of the class described, the combination with a hand operated calculating mechanism having a rotatable handle, a casing on which the base of said mechanism rests and a money drawer operable in said casing, a bar journaled transversely in said casing rearward of the end of said drawer, a hook fixed on said bar, a detent on said drawer engageable by said hook, an arm fixed on the bar, a lever pivoted in said casing, said lever having a part engaging said arm, means for holding said lever in operative position, a plunger carried at the op-

posite end of said lever and a cam fixed on 25 said handle adapted to depress said plunger and release said drawer co-incident with its operation.

2. In a device of the class described, the combination with a hand operated calculating mechanism having a rotatable handle, a casing on which the base of said mechanism rests and a money drawer operable in said casing, of a detent holding said drawer when in a closed position, means for projecting 30 said drawer when released, a bell fixed in said casing at the rear of said drawer, a hammer normally raised resiliently over said bell, a spring hook carried by said drawer engageable with said hammer, a cam 35 on said handle, and intervening levers operated by said cam for releasing said detent and permitting said drawer to move outwardly.

In testimony whereof I have signed my 40 name to this application.

CLIFFORD R. RANDALL.
